UNITED STATES PATENT OFFICE

MAURICE G. KLEMME, OF BELLEVILLE, ILLINOIS, ASSIGNOR TO EAGLE FOUNDRY COMPANY, OF BELLEVILLE, ILLINOIS, A CORPORATION OF ILLINOIS

HEATING STOVE

Application filed August 31, 1928. Serial No. 303,191.

My invention relates to heating stoves of the type wherein the gases or products of combustion may be given a direct or indirect course to the exit flue; and it has for its principal object a device which will control both the direct and indirect draft and which will prevent passage of the gases or products of combustion from the indirect flue through the exit flue when the device is in position to 10 secure a direct draft through said exit flue. Other objects are simplicity and cheapness of construction and compactness of design.

The invention consists principally in a heating stove comprising a combustion chamber having an exit flue and an indirect flue, and means for establishing direct communication between the combustion chamber and the exit flue or indirect communication between said chamber and said exit flue through 20 said indirect flue, said means operating to close communication between the indirect flue and the exit flue when the latter is in direct communication with the combustion chamber of the stove. The invention also consists in 25 the construction, combinations and arrangements of parts hereinafter described and claimed.

In the accompanying drawing, which forms part of this specification and wherein like 30 symbols refer to like parts wherever they occur,

Fig. 1 is a vertical central section through a heating stove embodying my invention;

Fig. 2 is a vertical cross-section through the 35 upper portion of the stove on the line 2—2 in Fig. 1; and

Fig. 3 is a horizontal cross-section through the stove on the line 3—3 in Fig. 1.

Referring to the accompanying drawing, 40 my invention is shown in connection with a circulating heating stove comprising a base 1, an ash pit 2 supported thereon and provided with an opening 4 affording access to said ash pit, a fire pot 5 supported on said 45 ash pit and provided at its bottom with a suitable dump grate 6, and a combustion chamber 7 located above said fire pot and provided with a substantially hemispherical top. The front wall of the combustion chamber is provided with the usual fuel receiving

opening 8; and the rear wall of said chamber is provided with the usual smoke outlet or exit flue 9. The stove is enclosed within a suitable casing 10, which is supported on the base 1 and is provided with a fire door 11 for closing the fuel receiving opening 8 of the combustion chamber 7 and an ash door 12 for closing the opening in the front of the ash pit 2. The construction of heating stove thus far described is well known and it is considered unnecessary to illustrate it in detail.

The rear portion of the dome of the combustion chamber 7 is provided with an indirect flue or passageway 13 whose upper end communicates with said chamber at the top thereof and whose lower end terminates adjacent to the inner end of the exit or outlet flue 9 leading from the rear wall of the combustion chamber. The end walls of the flue 13 extend downwardly on opposite sides of the exit or outlet flue 9 and are provided with pockets or bearings adapted to rotatably support the horizontal trunnions 14 of a damper 14, located opposite the inner end of the exit flue 9 and used to control combustion by regulating the draft through the direct and indirect flues 9 and 13, respectively. One of the trunnions of the damper projects through one side of the stove and the 55 enclosing casing therefor and is provided with a knob 15, whereby the damper may be manipulated. The damper 14 is shaped and arranged so that when it is rotated in a direction which will cause the upper portion 60 thereof to swing forwards and the lower portion to swing backwards, the upper edge of the damper abuts against the front wall of the indirect flue 13 and thus establishes communication between said flue and the exit flue, while the rear portion of the damper swings rearwardly and closes direct communication between the combustion chamber and said exit flue. When the damper is rotated in a reverse direction the 65 lower portion thereof swings forward and thus establishes direct communication between the combustion chamber and the exit flue while the upper portion of said damper swings rearwardly and thus closes communication.

100

cation between the indirect flue and the exit flue.

By the arrangement described, the damper may be manipulated so as to give the products of combustion a direct or circuitous course to the exit flue. It is noted as an important advantage of my invention that when the damper is manipulated to secure a direct draft for the products of combustion through the exit flue, communication between the inverted flue and the exit flue is completely cut off, thereby preventing the passage of any of the products of combustion through said indirect flue and thus causing a double draft which tends to check or "kill" the direct draft.

What I claim is:

1. A heating stove comprising a combustion chamber, an exit flue leading horizontally from said chamber adjacent to the lower end thereof, a downwardly extending indirect flue formed in the wall of said chamber and communicating therewith adjacent to the top thereof and adjacent to said exit flue, and a damper movably supported in said chamber opposite said exit flue and adapted to either admit the products of combustion directly into said exit flue or to admit them into said exit flue through said indirect flue, said damper being shaped and arranged to cut off communication between the adjacent ends of said indirect flue and said exit flue when moved to a position to establish direct communication between said exit flue and said chamber.

2. A stove comprising a combustion chamber having a heating dome, an exit flue communicating with said chamber adjacent to the lower end thereof, an indirect flue communicating at its upper end with the dome of said chamber and at its lower end with said chamber adjacent to said exit flue, and a damper movably supported in chamber adjacent to said exit flue and to the lower end of said indirect flue and adapted to either admit the products of combustion directly into said exit flue or to admit them into said exit flue through said indirect flue, said damper being shaped and arranged to close communication between the adjacent ends of said indirect flue and said exit flue when moved to a position to establish direct communication between said exit flue and said chamber.

3. A heating stove comprising a combustion chamber having a heating dome at the top thereof, an exit flue communicating with said chamber below said dome, an indirect flue formed in the wall of said dome and communicating at its upper end with the center of said dome and at its lower end with said combustion chamber adjacent to said exit flue, and a damper rotatably supported in said chamber opposite said exit flue and adapted in one position of its movement to establish communication between the indirect flue and the exit flue and to close direct com-

munication between the combustion chamber and said exit flue and adapted in the other position of its movement to establish direct communication between said combustion chamber and said exit flue and to close communication between said indirect flue and said exit flue. 70

4. A heating stove comprising a combustion chamber having a substantially hemispherical dome at the top thereof, an exit flue communicating with said chamber below said dome, an indirect flue formed in the curved wall of said dome and communicating at its upper end with the interior of said dome adjacent to the center thereof and at its lower end with said chamber adjacent to the upper portion of said exit flue, the end walls of said indirect flue extending downwardly on opposite side of the exit flue, a damper rotatably supported in said chamber between the downwardly extending walls of said indirect flue opposite said exit flue and adapted to give the products of combustion a direct course from the chamber to the exit flue or an indirect course from the dome of said chamber through said indirect flue to said exit flue, said damper being adapted to cut off communication between said indirect flue and said exit flue when moved to a position to establish direct communication between said exit flue and said chamber. 85 90

5. A heating stove comprising a combustion chamber and a horizontal exit flue leading from said chamber adjacent to the lower end thereof, a downwardly extending indirect flue formed in the wall of said chamber and communicating at its upper end with the upper portion of said chamber and communicating at its lower end with said chamber at a point adjacent to said exit flue, said indirect flue having an inner wall terminating at its lower end adjacent to the upper portion of said exit flue and having side walls extending downwardly on opposite sides thereof, and a damper located opposite said exit flue and mounted for vertical swinging movement towards and away therefrom between the opposing depending end walls of said indirect flue, said damper being adapted in one position of its swinging movement to establish communication between the indirect flue and the exit flue and to close direct communication between the combustion chamber and the exit flue, and being adapted in the other position of the swinging movement to establish direct communication between said combustion chamber and said exit flue and to close direct communication between said indirect flue and said exit flue. 100 105 110 115

Signed at St. Louis, Missouri, this 29 day 125 of Aug., 1928.

MAURICE G. KLEMME.
